UNITED STATES PATENT OFFICE.

JOSIAH F. JOHNSON, OF SWARTHMORE, PENNSYLVANIA, ASSIGNOR TO WESTINGHOUSE ELECTRIC AND MANUFACTURING COMPANY, A CORPORATION OF PENNSYLVANIA.

BLEEDER TURBINE.

Application filed June 8, 1923. Serial No. 644,255.

My invention relates to bleeder turbines and it has for an object to provide apparatus of the character designated which shall be capable of maintaining a substantially constant and predetermined bleeder pressure with a wide range of variation in the amount of motive fluid passing through the turbine or with a wide variation in the bleeder demand.

10 A further object of my invention is to provide interstage valve means in a bleeder turbine to control the admission of motive fluid to the low-pressure end thereof and which is connected to a valve in the bleeder line in such a way that the latter valve is fully opened and closed while the interstage valve is fully open and the interstage valve is opened and closed while the bleeder line valve is approximately wide open.

20 A further object of my invention is to provide an interstage valve for a bleeder turbine which is connected to a valve in a bleeder line by means arranged internally of the casing structure so that a minimum of exposed parts and packed joints is involved.

25 A further object of my invention is to provide, in connection with apparatus of the character referred to, means which is responsive to predetermined movements of the 30 governor-controlled valves in either direction for the purposes of closing the bleeder line valve so that, in case of excessive loads, all of the steam may be caused to pass through the turbine and, in case of shutting down of the turbine, the latter is effectively 35 isolated from the bleeder system, preventing the turbine from overspeeding by steam supplied from the bleeder system.

30 My present invention constitutes an improvement upon the type of bleeder turbine disclosed in my application, Serial No. 474,827, filed June 3, 1921, assigned to the Westinghouse Electric and Manufacturing Company, and it has for its particular object 45 to improve the valves and the valve-operating mechanisms in order to simplify them from a structural standpoint and to render them more practicable. Also, due to the 50 connection of the valve-operating mechanism to the governor-controlled valves, the closure of the bleeder line valve in case of overloads

or of shutting down of the turbine is assured.

Apparatus made in accordance with my invention is illustrated in the accompanying drawings, forming a part of this application, in which Fig. 1 is a side elevation of a turbine having my improvement applied thereto; Fig. 2 is a fragmentary sectional view of a bleeder turbine showing my improved valve mechanism applied thereto; Fig. 3 is a sectional view taken along the line III—III of Fig. 2; Fig. 4 is a fragmentary view, somewhat like Fig. 3, but showing the valves in a different operative position; Fig. 5 is an enlarged sectional view of the valve-actuating mechanism; Fig. 6 is a top plan view of the mechanism shown in Fig. 5; Fig. 7 is a sectional view of a steam chest and showing the governor-controlled valves; and Fig. 8 is a diagrammatic view showing the operative relation of various parts relating to my invention.

Referring now to the drawings for a better understanding of my invention, I show a bleeder turbine comprising a casing 10 and a rotor 11 carrying the energy-abstracting elements of a first or high-pressure section, at 12, and the energy-abstracting elements of a second or low-pressure section, at 13. The sections, at 12 and 13, are separated by means of interstage valve mechanism, at 14, and a bleeder conduit or connection 15 communicates with the casing 10 at the high-pressure side of the valve 14. A valve 16, preferably of the butterfly type, is arranged in the bleeder line or conduit 15, and the valves 14 and 16 are operated by mechanism, at 17, which is responsive both to pressure in the bleeder line and to the positions of governor-controlled valve mechanism, shown at 18, the latter being, in turn, actuated by a governor, at 19.

The interstage valve 14 consists of a stationary member 20 carried by the turbine casing 10 and a relatively movable member 21, which is retained in position with respect to the member 20 and which is provided with a gland 22 fitting with close clearance with respect to the rotor 11. The stationary member 20 is provided with a circumferential series of ports 23 which are relatively longer

in a circumferential direction than a series of cooperative ports 24 arranged in the movable valve member 21. This difference in the dimensions of the ports permits of movement of the valve member 21 before such valve member begins to restrict communication through the ports.

The butterfly valve 16 is pivoted internally of the bleeder line or conduit at 25 and 10 it is provided at its top with a crank arm 26 which is pivotally connected to a link 27, the latter, in turn, being pivotally connected to a crank arm 28 carried by the movable valve member 21.

15 The relationship of the crank arms carried by the valve members and the connecting link will more clearly appear from an inspection of Fig. 3. From this view, it will be seen that the crank arms 28 and 26 20 define acute angles at opposite sides of the center line *ab*, passing through the axes of the valve members so that, when the butterfly valve 16 is closed, its crank arm is in such a position as to receive a large tangential component of force transmitted from the arm 28 in order to open such valve.

As already pointed out, the ports 23 are longer in a circumferential direction than the ports 24. When the butterfly valve 16 30 is closed, the rear edges of the ports 24 are adjacent to the rear edges of the ports 23 so that the movable valve member 21 may undergo such movement without restriction of communication through these ports as 35 will be sufficient to substantially fully open the butterfly valve 16.

In Fig. 3, clockwise movement of the movable valve member 21 results in movement of the forward edges of the ports 24 toward 40 the forward edges of the ports 23, and when these edges substantially register, the butterfly valve will be moved to substantially its wide open position. Further movement of the movable valve member 21 takes place 45 with very slight movement of the butterfly valve 16; and, as will be seen from Fig. 4, the movable valve member 21 may reach a final position entirely restricting communication through the ports without any substantial disturbance of the wide-open position of the butterfly valve.

From the structure described, it will be apparent that the butterfly valve 16 is opened and closed while the interstage valve 55 14 is substantially wide open and that the interstage valve is opened and closed while the butterfly valve is approximately wide open. In other words, these valves are operated in a sequential manner so as to take care of wide variations in power and bleeder demands.

The movable valve member 21 of the interstage valve is provided with a crank arm 30 which is operatively connected to the operating mechanism, at 17, which is re-

sponsive both to bleeder pressure and to the governor-control valve mechanism.

The operating mechanism, at 17, will be understood from a consideration of Figs. 3 and 5. It includes an operating piston 31, 50 which is connected to the crank arm 30 by means of a piston rod 32. The operating piston 31 is arranged within an operating cylinder 33, and motive fluid is admitted to opposite ends of the latter, in order to 55 move the piston 31 in both directions, by suitable pilot valve mechanism, at 34, which is under the control of a pressure-responsive device 35 connected to the bleeder line beyond the butterfly valve 16 by means of a 60 conduit 36 and under the control of the governor, at 19, and the governor-operated valve mechanism, at 18.

65 The pilot-valve mechanism, at 34, comprises a cylinder 36 having motive fluid inlet passages 37 and motive fluid exhaust passages 38 and 38'. The cylinder is also provided with passages 39 and 40, arranged between the passages 37 and 38 and between the passages 37 and 38', respectively. The 70 passages 39 and 40 communicate with the passages 41 and 42, respectively, leading to the lower and to the upper ends of the operating cylinder 33. A piston valve 43, having piston portions 44, (see Fig. 5) is arranged within the cylinder 36 and it controls communication of the motive fluid supply passages 37 with the passages 39 and 40 and of the latter with the exhaust passages 38 and 38', respectively, so that motive fluid may be admitted to one side of the operating piston 31 and exhausted from the other side for moving the latter. The exhaust passages 38 of the cylinder 36 75 preferably connect with a common discharge 100 passage 45.

The mechanism for securing operation of the pilot valve 43 in response to bleeder line pressures and in response to load conditions of the turbine will now be described. The pressure-responsive device 35 includes a diaphragm member 47, which is subject to fluid pressure received from the conduit 36 and to the pressure of the spring 48 arranged above the diaphragm. The diaphragm is 110 connected to a stem 49, which, at its upper end, bears against knife edges 50 carried by the lever 51. The lever 51 has knife edges 52 which bear against a suitable bearing surface 53 of framework or stationary 115 part of the apparatus. Suitable weights 54 are carried by the lever 51 in order to vary the load on the diaphragm and consequently the required fluid pressure to move the latter 120 upwardly.

The lever 51 is pivotally connected, at 125 55, to a link 56, which is pivotally connected, at 57, to a floating lever 58, the latter lever being pivotally connected, at 59, to a link 60, which is pivotally connected, at 61, to a 130

lever 62, fulcrumed at 63, and having its outer end connected, at 63', to the pilot valve 43. With this arrangement, upon predetermined upward movement of the diaphragm 47 in response to an increase in bleeder pressure, the stem 49 moves upwardly, the lever 51 is tilted upwardly about its fulcrum 52, the link 56 moves upwardly, the floating lever 58 is tilted upwardly about the momentary fulcrum 58', with respect to a stem 31' carried by the operating piston 31, the link 60 moves upwardly, and the lever 62 tilts about the fulcrum 63 to move the pilot valve 43 downwardly so as to supply motive fluid below the piston 31 and to exhaust fluid from above the latter, resulting in counterclockwise movement of the movable valve member 21 to restrict the flow of motive fluid to the bleeder connection. This movement continues until the pilot valve is moved back to its cut-off position by the stem 31', the lever 58, the link 60, and the lever 62. In this way, the building up of bleeder pressure beyond a predetermined amount is limited.

In case the bleeder line pressure should fall slightly, the diaphragm 47 would move downwardly under the influence of the spring 48 and of the weight 54, with the result that the linkage connections referred to would cause the pilot valve 43 to move upwardly to place the space below the operating piston 31 in communication with the exhaust and the space above the operating piston in communication with the source of motive fluid under pressure, in which case the operating piston 31 would move downwardly to move the movable valve member 21 in a clockwise direction so as to increase the supply of steam being bled in order to maintain the bleeder pressure, this movement continuing until the pilot valve 43 is brought back to cut-off position due to movement of the operating piston 31.

Referring again to the interstage valve 14 and to the butterfly valve 16, in Fig. 3, the valves are shown in such a position that the turbine is capable of developing the maximum amount of power, the bleeder connection being practically cut off, while in Fig. 4, I show the valves in such a position that the turbine has its minimum power-developing capacity and a maximum bleeder capacity. These valves may, therefore, be moved by the mechanism just referred to in order to supply various power and bleeder demands over wide ranges.

It is desirable that the bleeder line should be cut off from the turbine in case of peak loads in order that the maximum power-developing capacity may be had and in case of shutting down of the turbine in order to avoid racing of the latter due to backflow of steam from the bleeder line through the low-pressure section, at 13. Accordingly, there-

fore, I provide a connection between the lever 62 of the pilot valve 43 and the governor-controlled valve mechanism, at 18, in order to secure downward movement of the pilot valve 43, upward movement of the operation piston 31, and counterclockwise movement of the movable valve member 21 in order to secure closure of the butterfly valve 16 in case of a predetermined light load or a predetermined overload.

The lever 62 is moved downwardly by means of a lever 65 fulcrumed at 66 and pivotally connected, at 67, to the upper end of the stem 68 bearing the fulcrum connection 63. A spring 69 cooperates with the lower end of the stem 68 in order to maintain the latter normally in an upper position. Whenever the lever 65 is moved upwardly, the stem 68 is forced downwardly, compressing the spring 69, and the lever 62 is tilted downwardly about the pivotal connection 61 to move the pilot valve 43 downwardly so as to secure upward motion of the operating piston 31 and closure of the butterfly valve 16. The governor-controlled valve mechanism for securing operation of the lever 62 in this way will now be described.

Referring to Fig. 7, the governor-controlled admission valve mechanism, at 18, consists of a primary valve 70 and a secondary valve 71 for controlling the passage of steam from the supply 72 to the turbine passages 73 and 74, respectively. The valves 70 and 71 are connected to stems 74' and 75, respectively, and the latter are pivotally connected, at 76 and 77, respectively, to a lever 78. The lever 78 is pivotally connected, at 79, to suitable governor-operated mechanism, at 80. For example, I show the governor-operated mechanism, at 80, consisting of downwardly extending links 81 which are pivotally connected to a lever 82, the latter, as may be seen from Figs. 1 and 8, being fulcrumed, at 83, and connected to the movable element of the governor, at 19. A spring 84 is connected to the lever 78 in order to assure that, upon upward movement of the governor-operated mechanism, at 80, the primary valve shall first be opened. In order that the secondary valve 71 may be opened after the primary valve 70 is wide open, it is necessary that the upward movement of the lever 78 in the manner referred to should be limited. Therefore, I show an adjustable abutment 86 which limits upward movement of the left-hand end of the lever 78, so that the right-hand end of the latter may be moved upwardly against the force of the spring 84 to open the secondary valve 71 after the primary valve 70 is fully opened.

The governor-controlled valve mechanism, at 18, includes mechanism, whereby, upon extreme limits of adjustment of the primary and secondary valves 70 and 71, the lever 130

65 is moved so as to tilt the lever 62 downwardly to secure closure of the butterfly valve 16 in the manner already referred to. I, therefore, provide a lever 87, fulcrumed 5 at 88, and having one end pivotally connected, at 89, to a link 90, which is pivotally connected, at 91, to one end of the lever 65. If the lever 87 is tilted about the fulcrum 88 so that the link 90 and the adjacent end of 10 the lever 65 are moved upwardly then the butterfly valve 16 will be closed in the manner stated. The governor-operated lever 78 is arranged to tilt the lever 87 in this manner upon extreme limits of valve adjustment. 15 One end of the lever 87 is pivotally connected, at 92, with respect to a link 93 which is provided with an adjustable abutment 94 at its lower end. The lever 78 has a slidable connection 95 with respect to the link 93 20 so that, when the primary valve 70 is closed, the lever 78 comes in contact with the abutment 94 to pull down the link 93 and tilt the lever 87 about the fulcrum 88 in order to pull the link 90 upwardly and tilt the 25 adjacent end of the lever 65 upwardly for the purpose of securing closure of the butterfly valve 16. The other end of the lever 78 has a slidable connection 96 with respect to the link 90 and the latter carries an adjustable abutment 97. Hence, after the 30 secondary valve 71 is opened to a predetermined extent, the lever 78 comes in contact with the abutment 97 with the result that the link 90 and the adjacent end of the lever 65 are pulled up for the purpose of closing the butterfly valve 16.

The operation of apparatus made in accordance with my invention will be better understood from a consideration of dia- 40 grammatic Fig. 8 from which it will be seen that the pressure-responsive device 35 acts upon an increase or a decrease in bleeder pressure to move the lever 62 through the intermediary of the lever 51, the link 56, the lever 58, and the link 60 in order to move the pilot valve 43 upwardly or downwardly to secure movement of the interstage valve 14 in one direction or the other. When the butterfly valve 16 is closed the 45 ports 23 and 24 of the interstage or grid valve afford full communication between the turbine sections, at 12 and 13. This is the position for maximum power development. With movement of the valve member 21 50 in a direction to close the interstage or grid valve 14, the butterfly valve 16 is fully opened before restriction of the interstage or grid valve 14 commences; and, while the butterfly valve 16 is approximately wide open, further movement of the valve member 21 may take place to secure closure and opening of the interstage or grid valve 14. With closure of the interstage or grid valve 55 14 the parts are in a position for the satisfaction of a maximum bleeder demand.

The pressure-responsive device 35 there- 70 for serves to secure operation of the valves in such a way as to maintain the bleeder line pressure as near as possible to a desired value. Upon a tendency of the bleeder pres- 75 sure to increase the interstage valve 14 is opened, or, if the latter is opened the butterfly valve 16 is moved so as to restrict the supply of steam to the bleeder line; where- 80 as, upon a decrease in bleeder line pressure, 75 the butterfly valve 16 is opened wider, or, if the latter is wide open, the interstage valve 14 is moved in a closing direction.

If the bleeder line pressure tends to in- 85 crease, the movable valve member 21, with respect to Figs. 3 and 4, moves in a counterclockwise direction in order to secure movement of the butterfly valve 16 toward a closing position so that full communica- 90 tion takes place between the turbine sections at 12 and 13 and any diminution in bleeder pressure must occur by movement of the butterfly valve 16 in a closing direction. In case of increasing bleeder demand, with the interstage or grid valve 14 wide open and with the butterfly valve 16 substantially wide open, a decrease in bleeder line pressure results in further clockwise movement of the valve membr 21 to restrict communica- 95 tion between the turbine sections, at 12 and 13, so that more of the steam may be diverted for passage through the bleeder line, the limit being reached when the low- 100 pressure section, at 13, is wholly cut off from the high-pressure section, at 12, and the but- 105 terfly valve at 16 is approximately wide open.

The governor-operated lever 78 for the primary and secondary valves 70 and 71 105 serves to move the lever 87 so as to pull the link 90 and the adjacent end of the lever 65 upwardly so as to push the lever 62 downwardly about the pivotal connection 61 in order that the operating piston 31 may be moved upwardly to secure closure 110 of the butterfly valve 16 either when the primary and secondary valves are substan- 115 tially closed, as when shutting down the turbine, or with such valves substantially wide open which occurs when the turbine is overloaded to a predetermined extent.

From the foregoing it will be apparent that I have devised a bleeder turbine which is capable of satisfying wide ranges of bleeder and power demands and which is capable of being automatically cut off from the bleeder system when it is being shut down.

While I have shown my invention in but one form, it will be obvious to those skilled in the art that it is not so limited, but is susceptible of various other changes and modifications, without departing from the spirit thereof, and I desire, therefore, that only such limitations shall be placed there- 125 130

upon as are imposed by the prior art or as are specifically set forth in the appended claims.

What I claim is:

5. 1. In a bleeder turbine, the combination of a bleeder line valve, a governor, and means operated by the governor for closing the bleeder line valve upon predetermined overspeeds and underspeeds of the turbine. 70
10. 2. In a bleeder turbine, the combination of primary and secondary valves for the turbine, a bleeder line valve, and means for closing the bleeder line valve upon predetermined closing movement of the primary valve and upon predetermined opening movement of the secondary valve. 75
15. 3. In a bleeder turbine, the combination of an admission valve, a bleeder line, a valve in the bleeder line, a pressure-responsive device connected to the bleeder line beyond the bleeder line valve, means operated by the pressure-responsive device to open and close the bleeder line valve, and means subject to the closure of the admission valve to close the bleeder line valve. 80
20. 4. In a bleeder turbine, the combination of an interstage valve, a bleeder line, a valve in the bleeder line, a pressure-responsive device connected to the bleeder line beyond the bleeder line valve for operating the interstage valve, and means for operating the bleeder line valve from the interstage valve. 85
25. 5. In a bleeder turbine, the combination of an interstage valve, a bleeder line, a valve in the bleeder line, a pressure-responsive device connected to the bleeder line beyond its valve, a fluid relay interposed between the pressure-responsive device and the interstage valve, and means for connecting the interstage valve and the bleeder line valve so that the latter is operated by movement of the former. 90
30. 6. In a bleeder turbine, the combination of a bleeder line, a valve in the bleeder line, a pressure-responsive device connected to the bleeder line beyond the valve, fluid relay mechanism subject to the pressure-responsive device for opening and closing the valve, an admission valve for the turbine, and means dependent upon closure of the admission valve to operate the relay to close the bleeder line valve. 95
35. 7. In a bleeder turbine, the combination of an interstage valve, a bleeder line, a valve in the bleeder line, a pressure-responsive device connected to the bleeder line beyond its valve, fluid relay mechanism subject to the pressure-responsive device for controlling the interstage valve, mechanism for transmitting motion from the interstage valve to the bleeder line valve, and admission valve, and means responsive to predetermined closing movement of the admission valve to operate on the relay mechanism for closing the bleeder line valve. 100
40. 8. In a bleeder turbine, the combination of primary and secondary valves, a lever having its ends connected to said valves, means for biasing the lever so that the primary valve is opened before the secondary valve and closed after the latter, a bleeder line, a valve in the bleeder line, and means responsive to predetermined downward movement of the primary-valve-end of the lever and to predetermined upward movement of the secondary-valve-end of the lever for closing the bleeder line valve. 105
45. 9. In a bleeder turbine, the combination of a bleeder line, a valve in the bleeder line, primary and secondary valves for the turbine, a lever connected to the primary and secondary valves, and means for closing the bleeder line valve upon predetermined downward movement of the primary-valve-end of the lever and upon predetermined upward movement of the secondary-valve-end of the lever. 110
50. 10. In a bleeder turbine, the combination of an interstage valve, a bleeder line, a valve in the bleeder line, means for connecting the valves so that the bleeder line valve is moved by the interstage valve, a pressure-responsive device connected to the bleeder line beyond its valve, a relay between the pressure-responsive device and the interstage valve, primary and secondary valves for the turbine, and means dependent upon a predetermined closing movement of the primary valve and upon a predetermined opening movement of the secondary valve for rendering the relay operative to move the interstage valve in order to close the bleeder line valve. 115
55. 11. In a turbine, the combination of a high-pressure section, a low-pressure section, a valve between the sections having a greater range of movement than its throttling range, a bleeder line communicating with the turbine at the high-pressure side of said valve, a valve for controlling the admission of motive fluid to the bleeder line, and means arranged internally of the turbine for opening and closing the bleeder line valve during non-throttling movement of said first valve. 120
60. 12. In a turbine, the combination of an interstage valve having a greater range of movement than its throttling range, a bleeder line, a valve in the bleeder line, and means operated by the interstage valve for opening and closing the bleeder line valve during non-throttling movements of the former. 125
65. 13. In a turbine, the combination of a rotary interstage valve having a range of rotary movement greater than its throttling range, a bleeder line, a butterfly valve in the bleeder line, crank arms carried by the valves, and a link for connecting the crank arms. 130
70. 14. In a turbine, the combination of an interstage valve having a rotary member, a

bleeder line, a rotary valve in the bleeder line, crank arms carried by the valves, and a link for connecting the crank arms.

15. In a turbine, the combination of high and low-pressure sections, a valve between the sections, a bleeder line communicating with the turbine at the high-pressure side of the valve, a valve in the bleeder line, and means actuated by the first valve for opening and closing the bleeder line valve.

16. In a bleeder turbine, the combination of an interstage valve comprising a stationary member having one or more openings therein and a movable member having corresponding opening or openings of less extent in the direction of travel than the first opening or openings, a bleeder line valve, and means operated by the movable member of the interstage valve for opening and closing the bleeder line valve.

17. In a bleeder turbine, the combination of an interstage valve comprising a stationary valve member having a plurality of openings therein, and a movable member having corresponding openings of less extent in the direction of travel than the first openings, a bleeder line, a valve in the bleeder line, and means for actuating the bleeder line valve from the movable member of the first valve and so arranged that the bleeder line valve is closed when the interstage valve is in its extreme position of maximum opening.

18. In a bleeder turbine, the combination of an interstage valve having a greater range of movement than its throttling movement, a bleeder line, a bleeder line valve, and variable motion means for connecting the valves so that the bleeder line valve is opened and closed during non-throttling movements of the interstage valve and the latter is opened and closed while the bleeder line valve is substantially wide open.

19. In a bleeder turbine, the combination of an interstage valve, a bleeder line, a bleeder line valve, a variable motion linkage means for connecting the valves so that the interstage valve is opened and closed while the bleeder line valve is substantially fully open.

20. In a bleeder turbine, the combination of a grid valve within the turbine, a bleeder line, a valve in the bleeder line and mechanism for transmitting motion from the grid valve to the bleeder line valve.

21. In a bleeder turbine, the combination of a grid valve within the turbine having a greater range of movement than its throttling range, a bleeder line, a valve in the bleeder line, and mechanism arranged between the grid valve and the bleeder line valve for opening and closing the latter during non-throttling movements of the former.

22. In a bleeder turbine, the combination of a rotary grid valve within the turbine, a

bleeder line communicating with the turbine, a valve in the bleeder line, crank arms carried by the valves, and a link for connecting the crank arms.

23. In a bleeder turbine, the combination of a rotary grid valve within the turbine having a greater range of movement than its throttling range, a bleeder line communicating with the turbine, a valve in the bleeder line, mechanism for transmitting motion from the grid valve to the bleeder line valve, a pressure-responsive device connected to the bleeder line beyond the bleeder line valve, and means operated by the pressure-responsive device for moving the grid valve.

24. In a bleeder turbine, the combination of an admission valve for the turbine, a grid valve within the turbine, a bleeder line communicating with the turbine, a valve in the bleeder line, mechanism for transmitting motion from the grid valve to the bleeder line valve, a pressure-responsive device connected to the bleeder line beyond the bleeder line valve, a relay between the pressure-responsive device and the grid valve, and means dependent upon predetermined closing movement of the admission valve for rendering the relay operative.

25. In a bleeder turbine, the combination of a grid valve within the turbine, a bleeder line communicating with the turbine, a valve in the bleeder line, mechanism for transmitting motion from the grid valve to the bleeder line valve, a pressure-responsive device connected to the bleeder line beyond the bleeder line valve, a double-acting motor device for the grid valve including a control valve, and means for operating the control valve from the pressure-responsive device.

26. In a bleeder turbine, the combination of a grid valve within the turbine having a greater range of movement than its throttling range, a bleeder line communicating with the turbine, a valve in the bleeder line, mechanism for transmitting motion from the grid valve to the bleeder line valve so that the latter is opened and closed during non-throttling movements of the grid valve, a pressure-responsive device connected to the bleeder line beyond the bleeder line valve, a double-acting motor device connected to the grid valve and including a control valve, and means for operating the control valve from the pressure-responsive device.

27. In a bleeder turbine, the combination of an admission valve, a grid valve within the turbine, a bleeder line communicating with the turbine, a valve in the bleeder line, mechanism for transmitting motion from the grid valve to the bleeder line valve, a pressure-responsive device connected to the bleeder line beyond the bleeder line valve, a double-acting motor device connected to the grid valve and including a control valve,

means for operating the control valve from the pressure-responsive device, and means rendered operative by predetermined closing movement of the admission valve for moving the control valve to move the grid valve to secure closure of the bleeder line valve.

28. In a bleeder turbine, the combination of primary and secondary valves, a grid valve within the turbine having a greater range of movement than its throttling range, a bleeder line communicating with the turbine at the high-pressure side of the grid valve, a valve in the bleeder line, mechanism for transmitting motion from the grid valve to the bleeder line valve so that the bleeder line valve is opened and closed during non-throttling movements of the grid valve and the grid valve is opened and closed while the bleeder line valve is substantially wide open, a pressure-responsive device connected to the bleeder line beyond the bleeder line valve, a double-acting motor device connected to the

grid valve and including a control valve, means for operating the control valve from the pressure-responsive device, and means rendered operative upon predetermined closing movement of the primary valve and upon predetermined opening movement of the secondary valve for moving the control valve so that the motor device moves the grid valve to secure closing movement of the bleeder line valve.

29. In a bleeder turbine, the combination of an interstage valve, a bleeder line, a bleeder line valve, means for controlling one of said valves, and variable motion means separate from said control means for connecting the valves so that the interstage valve is opened and closed while the bleeder line valve is substantially fully open.

In testimony whereof, I have hereunto subscribed my name this 1st day of June, 1923.

JOSIAH F. JOHNSON.
